BUBBLE-FORMING WRITING INSTRUMENT

Clayton F. Ritchie, Chicago, Ill.

Application April 6, 1950, Serial No. 154,389

2 Claims. (Cl. 41—10)

1

This invention relates to a bubble-forming writing instrument in the form of a bubbling pencil and pen adapted for use by children and others as a combined writing instrument and novelty.

An object of this invention is to provide a novel bubble-forming writing instrument in the form of a bubbling pencil and pen embodying the novel features of construction and the novel mode of operation hereinafter described.

Another object of the invention is to provide a novel writing instrument which will form bubbles under the heat of the user's body as applied thereto by the fingers during the writing operation.

Other objects will appear hereinafter.

In the drawing:

Fig. 1 is an elevational view illustrating the manner in which the new bubble-forming writing instrument may be used;

Fig. 2 is an elevational view of the present invention as embodied in a bubble-forming pen;

Fig. 3 is an elevational view of the present invention as embodied in a bubble-forming pencil;

Fig. 4 is an enlarged fragmentary longitudinal sectional view illustrating the construction of the new bubble-forming writing instrument as embodied in a writing pen;

Fig. 5 is an enlarged fragmentary view of the present invention as embodied in a writing pencil, as illustrated in Fig. 3, partly in section and partly in elevation;

Fig. 6 is a transverse sectional plan view on line 6—6 in Fig. 4; and

Fig. 7 is a transverse sectional plan view on line 7—7 in Fig. 4.

The present invention in the form of a bubble-forming writing instrument is illustrated in the drawings as embodied in two of its permissible forms, namely, as a bubble-forming writing pen, as illustrated in Figs. 1, 2, 4, 6 and 7, and as a bubble-forming writing pencil, as illustrated in Figs. 3 and 5 of the drawing. However, since the construction of the new bubble-forming writing instrument, in both of the forms referred to is, in general, quite similar, the invention will first be described as the bubble-forming pen which is illustrated in Figs. 1, 2, 4, 6 and 7 and thereafter the invention will be described as to the bubble-forming pencil form of the invention which is illustrated in Figs. 3 and 5 of the drawing.

Referring to the form of the present invention which is illustrated in Figs. 1, 2, 4, 6 and 7 of

the drawing, the new bubble-forming writing instrument is generally indicated at 10, and embodies a substantially cylindrical housing or barrel 11 having a reduced and externally threaded upper end portion 12. The barrel or cylinder is preferably made of a transparent resinous plastic material such, for example, as "Lucite," and has a centrally arranged longitudinally extending interior bore 13 which is adapted to hold a supply of a liquid 14 which will volatilize below the normal temperature of the human body, so as to form bubbles, as will be described hereinafter.

An internally threaded sleeve 15 is threaded onto the reduced externally threaded upper end portion 12 of the barrel 11 and this sleeve 15 has a central passage 16 extending therethrough and the passage 16 terminates at its upper end in a reduced internally threaded passage 17 having a closure member, in the form of a small screw or bolt 18, threaded therein. A closure cap 20 is detachably mounted in any suitable manner, as by means of a frictional fit, upon a shoulder 31 which is formed upon the external surface of the sleeve 15, and the external surface of the upper portion of the sleeve 15 is reduced in diameter to provide a space 19 between the same and the wall of the closure cap 20, as shown in Fig. 4. The closure cap 20 has a centrally arranged vent opening 21 formed in the end wall 22 thereof (Fig. 4).

An escape vent or pressure-relief opening 23 is formed in the side wall of the reduced upper end portion of the sleeve 15 and this vent 23 opens into the passage 19 which, in turn, communicates with the vent opening 21 which is formed in the closure cap 20 (Fig. 4).

The barrel or cylinder 11 has a reduced externally threaded lower end portion 24 and an internally threaded sleeve 25 is threaded thereon. This sleeve is preferably formed of heat-conductive metal or other material, such as a suitable aluminum alloy.

A writing pen unit or head 26 is mounted in the sleeve 25 and is held therein in any suitable manner, as by a pressed fit or frictional engagement with the internal surface of the lower portion of the sleeve 25, or otherwise, and this writing pen unit or head 26 has a series of stepped portions 27 formed therein. As shown in Fig. 4, the stepped portions 27 are of decreasing diameter, as they progress upwardly (Fig. 4), thereby providing a chamber 28 between the wall of the sleeve 25 and the outer surface of the head 26. This chamber 28 communicates with, and is, in effect, an extension of the chamber

13 in the barrel 11, so that the liquid 14 in the chamber or barrel 11 will flow into the chamber 28.

A suitable writing instrument which may be a pen point 29, of conventional design, is mounted in the head 26 and in this instance the pen point 29 is fed from an ink passage 30 formed in the head 26.

In the use of the form of the invention which is illustrated in Figs. 1, 2, 4, 6 and 7, a supply of a suitable fluid 14 may be placed in the interior chamber 13 of the barrel 11 and for this purpose I prefer to use a fluid which will volatilize and bubble at a low temperature, well below the temperature of the human body, and which is non-toxic and non-inflammable liquid. Thus I have found that a suitable liquid for this purpose is decafluorobutane, which has a boiling point of 27° F., and is non-toxic and non-inflammable. To introduce the liquid 14 into the chamber 13 it is merely necessary to remove the closure cap 20 and the closure screw 18 and pour the liquid 14 into the chamber 13 through the passages 17 and 16.

When the invention is used as a writing pen the same is grasped by the fingers around the sleeve 25 whereupon the heat of the fingers around the lower portion of the heat-conductive sleeve 25, which as a finger grip, will heat the liquid 14 in the chamber 27 above its boiling point and cause the same to form bubbles 31 (Fig. 1) which will flow upwardly through the chamber 13 and will be visible through the transparent barrel 11, thereby create a novel bubbling effect while, at the same time, the new writing instrument will serve its function as a pen.

The present invention as shown in Figs. 3 and 5 of the drawing is embodied in a bubble-forming writing pencil and those parts thereof which are similar to corresponding parts in the form of the invention shown in Figs. 1, 2, 4, 6 and 7 have been given similar reference numerals followed by the additional and distinguishing reference character "a."

In the form of the invention illustrated in Figs. 3 and 5 of the drawing, a lead propelling unit 32, of the self-propelling type, and of conventional design, is mounted in the sleeve 25a, and a chamber 33 is formed in the head 25a, this chamber 33 communicating with and forming, in effect, an extension of the chamber 13a.

The bubble-forming writing instrument 10a, shown in Figs. 3 and 5 of the drawing, embodies a tip or nib 34 having a writing rod or so-called "lead" 35 mounted therein and which is adapted to be propelled by the propelling mechanism 32.

The upper end portion of the writing instrument or bubble-forming pencil, which is shown in Figs. 3 and 5 of the drawing, is the same in construction and in operation as the upper portion embodied in the construction illustrated in Figs. 1, 2, 4, 6 and 7, and as shown in Fig. 4, and hence need not be described again herein.

In the use of the form of the invention shown in Figs. 3 and 5 of the drawing, the chamber 13a in the barrel 11a may be filled with a low-temperature volatilizing fluid 14a, which may be the same as the fluid 14 hereinbefore described, and this fluid will flow from the chamber 13a into the chamber 33 wherein it will be volatilized by the temperature of the user's fingers gripping

the sleeve 25a during the writing operation, thereby creating a stream of bubbles which will flow upwardly through the transparent barrel 11a, thereby creating a novel bubbling effect while, at the same time, the new writing instrument performs its writing function as a pencil.

It will thus be seen from the foregoing description, considered in conjunction with the accompanying drawing, that the present invention has the desirable advantages and characteristics, and accomplishes its intended objects, including those hereinbefore pointed out and others which are inherent in the invention.

I claim:

1. A device of the character described comprising an elongated rounded plastic barrel having an elongated and open-ended internal chamber filled with a liquid of a boiling point substantially below normal human body temperature, removable closure cap means secured to the upper end of the barrel and including a vent opening and a refill inlet both communicable with the internal chamber in the barrel, a metallic sleeve secured to the lower end of the barrel and being of substantially greater heat conductance than the barrel, an element within the sleeve having successive sections of decreasing diameter tapering upwardly toward and being in alignment with the lower end of the said internal chamber, the sleeve encircling the said sections of the said element whereby facing portions of the sleeve and element together define an annular chamber constituting a lower extension of the said elongated chamber, the exterior portions of the barrel, sleeve, and closure cap means being of a size and configuration corresponding to that of a writing implement, and the thickness of the walls of the metallic sleeve at the said annular passage being such that the liquid in the transparent barrel is heated to boiling when grasped between the fingers.

2. A device according to claim 1 in which the closure cap means includes a first sleeve threaded to an upper extension of the transparent barrel and a second sleeve frictionally mounted over and about a portion of the said first sleeve, the said first and second sleeves having an outside diameter corresponding to that of the transparent barrel and metallic sleeve, the metallic sleeve being threaded to a lower extension of the transparent barrel, and the liquid in the barrel being decafluorobutane.

CLAYTON F. RITCHIE.
